UNITED STATES PATENT OFFICE.

ALEXANDER NYMAN, OF WILKINSBURG, PENNSYLVANIA, ASSIGNOR TO WESTINGHOUSE ELECTRIC & MANUFACTURING COMPANY, A CORPORATION OF PENNSYLVANIA.

LOUD-SPEAKING RECEIVER.

Application filed September 12, 1922. Serial No. 527,630.

My invention relates to sound reproducing apparatus and particularly to telephone receivers.

One object of my invention is to provide a new embodiment of a loud speaking device, wherein signal currents are faithfully translated into sound waves, and vice versa, without distortion.

Another object of my invention is to provide an extremely simple loud speaking receiver having readily adjustable parts and susceptible of inexpensive quantity production in existing automatic machinery.

According to my invention, I provide an instrument for accomplishing the above-mentioned desired results comprising a permanent magnet having divided magnetizable polar projections extending from one end thereof, the ends of the extensions being disposed in spaced relation. A vibratory magnetizable armature member has one end secured to the remaining end of the permanent magnet and the other end interposed between the ends of the polar projections in balanced relation thereto. A magnetizing winding is provided for disturbing the balanced condition of the armature in accordance with the signal currents, and a diaphragm of conical shape is mechanically associated with the armature member, whereby the armature vibration may be translated into sound waves.

With these and other objects in view, my invention further consists in the details of construction and operation hereinafter described and claimed and illustrated in the accompanying drawing, wherein:

Figure 1 is a top plan view of one embodiment of my invention, the diaphragm being removed.

Fig. 2 is a vertical longitudinal sectional view of the device shown in Fig. 1 taken on the line II--II thereof;

Fig. 3 is a similar view, the sectional plane being indicated by the line III--III of Fig. 1.

In the illustrated form of embodiment of my invention, I provide a sound-wave translating device 1 comprising a substantially circular permanent magnet 2 having its end portions or poles 3 and 4 disposed in laterally and vertically spaced relation. The permanent magnet 2 thus forms a magnetic circuit having an air gap 5 therein which is

determined by the distance between the ends 3 and 4 thereof.

An electromagnet 6 is provided comprising a core member 7 and an energizing winding 8. Secured to opposite ends of the core member 7, are pressed steel members 9 and 11 which are so bent as to arrange free end portions 12 and 13 thereof in spaced relation with a relatively small air gap 14 therebetween, thereby causing the portions 12 and 13 to serve as poles for the electromagnet 6. The magnetic circuit of the electromagnet thus includes the core 7, the steel member 9, the air gap 14 and the steel member 11. The electro-magnet 6 may be secured to the top side of the end portion 3 of the permanent magnet 2 by means of an extension 15 of the upper steel frame 9.

A vibratory magnetizable armature construction 16 comprises an armature member 17 which is vibratably positioned in the air gap 14 by means of a spring member 18 having one end secured to the armature member 17 and having the other end secured to the end portion 4 of the permanent magnet 2. Parallel paths are thus provided for the magnetic circuit of the permanent magnet 2 by the action of the steel members 9 and 11, the parallel paths being reunited in the armature construction 16. It is understood that my invention is not to be strictly limited to the armature construction 16, just described, and that the same may be replaced by a single resilient armature member consisting of magnetizable material.

The free end of the armature member 17 may be rigidly secured, by means of a connecting link 22, to the midpoint 23 of a diaphragm 24 of conical shape. A diaphragm of the shape stated is provided because of its greater rigidity in comparison to the ordinary flat diaphragm. The diaphragm 24, further distinguishes from the ordinary design in that the periphery thereof is not rigidly secured to a supporting member and hence may vibrate with substantially the same intensity as the center portion thereof. Attention is directed to the fact that the diaphragm 24, the connecting link 22 and the armature member 17 are supported as a single unit from the lower end of the permanent magnet 2.

When the armature 17 is positioned substantially midway between the two end por-

tions 12 and 13, which are of the same polarity, substantially no force is exerted on the armature member 17, tending to move the same. The armature 17 is thus under the effect of balanced opposing forces.

When a current, however, is caused to traverse the exciting winding 8 of the electromagnet 6 in one direction, a force is exerted on the armature member 17 by the 10 pole members 12 and 13 of the electromagnet 6 tending to move the armature 17 in one direction, and thus the balanced condition of the armature 17 is disturbed in one direction. When a current is caused to traverse the exciting winding 8 in the opposite direction, the magnetic forces exerted on the armature member 17 by the pole members 12 and 13 are reversed and the armature 17 moves in an opposite direction.

20 It can thus be seen that when the magnetizing winding 8 is supplied with vibratory electrical energy, as found, for instance, in currents modulated in accordance with sound waves, the armature member 17 or 25 armature construction 16 is caused to vibrate in accordance with the variations in the currents. The vibratory motion of the armature member 17 being translated to the diaphragm 24, sound waves of corresponding 30 vibration frequency ensue. In order to simplify the description of my invention and to facilitate a clear understanding of the same, I have eliminated from the description and drawings such portions of the 35 general structure as are well known to those skilled in the art.

Among the several advantages characteristic of my invention are simplicity in arrangement, economy in manufacture and 40 efficiency of operation. At no time is the diaphragm under tension, thereby simplifying the construction as well as increasing the efficiency of operation of the apparatus as a whole, inasmuch as the possibility of 45 distortion, resulting from harmonics in the diaphragm vibration, is eliminated. The light construction of the armature makes possible the attainment of a high resonance pitch for the several vibratory elements as 50 a whole and hence substantially no distortion is introduced by the same within the audible frequency range.

While I have described a certain embodiment of my invention for the purpose of illustrating the underlying principles and theory of operation thereof, it is apparent that certain changes and modifications may be made therein without departing from the spirit of my invention. I desire, therefore, that only such limitations shall be imposed thereon as are indicated in the appended claims or are demanded by the prior art.

I claim as my invention:—

1. In a translating device, the combination with a permanent magnet of a general 65 horse-shoe shape, an alternating-current magnet comprising a coil with a magnetizable core disposed within the horse-shoe magnet in an axis substantially perpendicular to the plane of the horse-shoe magnet, a 70 magnetizable supporting member connecting one end of the alternating-current magnet to one end of said horse-shoe magnet, pole pieces connected to the respective ends of the alternating current magnet and having 75 parallel spaced pole faces substantially parallel to the plane of the horse-shoe magnet, a resilient magnetizable armature construction secured to the other end of the horse-shoe magnet and extending between 80 said pole faces, a diaphragm disposed in spaced substantially parallel relation to said horse-shoe magnet, and a connecting means between said diaphragm and said armature construction.

2. In a translating device, a magnet of approximately ring shape, the ends of said magnet being spaced apart in a direction at an angle to the plane of the ring, a winding 90 having its axis approximately parallel to the axis of said ring and a core of magnetic material for said winding magnetically connected to one end of said magnet, magnetic members extending from the ends of said core into proximity with each other and a 95 vibratory magnetic arm extending from the other end of said magnet into the space between said magnetic members, said members and arm being within the periphery of said ring.

In testimony whereof, I have hereunto subscribed my name this 30th day of August 1922.

ALEXANDER NYMAN.
